UNITED STATES PATENT OFFICE.

JOHN S. NELSON, OF SIOUX FALLS, SOUTH DAKOTA.

AIR-MOISTENER AND DUST-COLLECTOR.

1,305,926.

Specification of Letters Patent. Patented June 3, 1919.

Application filed May 3, 1917. Serial No. 166,213.

To all whom it may concern:

Be it known that I, JOHN S. NELSON, a citizen of the United States, residing at Sioux Falls, in the county of Minnehaha and State of South Dakota, have invented certain new and useful Improvements in Air-Moisteners and Dust-Collectors; and I do declare the following to be a full, clear, and exact description of the invention, such 10 as will enable others skilled in the art to which it appertains to make and use the same.

This invention relates generally to furnaces, but more particularly to certain new and useful improvements in air moisteners and dust collectors adapted to be connected to the cold air pipe of a hot air furnace.

One object of the invention is to provide means for moistening cold air as it is fed 20 into a hot air furnace, said means requiring practically no attention, and being of such construction that it will not get out of order.

Another object of the invention is to provide means which will serve to collect all 25 particles of dust contained in the air as it is being supplied to a hot air furnace in addition to moistening such air.

A further object of the invention is to 30 generally improve upon devices of this class by the provision of an extremely simple, strong, durable and inexpensive construction, one which will be efficient and reliable in operation and well adapted to the purpose for which it is designed.

With these and other objects in view, the 35 invention consists of certain novel features of construction, and the combination and arrangement of parts as will be hereinafter fully described and claimed.

In the accompanying drawing forming a 40 part of the application, in which similar reference characters designate like parts throughout the several views:

Figure 1 is a side elevation of an ordinary 45 hot air furnace, showing a device constructed in accordance with this invention attached to the cold air pipe thereof;

Fig. 2 is an enlarged front elevation of the device;

Fig. 3 is a central vertical sectional view of the same; and

Fig. 4 is a horizontal sectional view of the device taken on the plane indicated by the line 4—4 of Fig. 3.

Referring more particularly to the drawing, the reference numeral 1 designates a

casing which is rectangular or cubical in configuration, and which is preferably constructed of sheet metal. Fixed to the top 2 and bottom 3 of the casing in any suitable 60 manner and extending centrally from the same are nipples 4 and 5 respectively by which the casing is attached to and supported by the cold air pipe *a* of the hot air furnace A.

One side, or in fact, the front of the casing is provided with a rectangular-shaped opening 6, and extending transversely through the casing from this side to the opposite side thereof and secured to these 70 sides is a pair of right-angular tray supporting guides 7. Corresponding ends of the guides 7 are disposed adjacent the lower corners of the opening 6 to support a tray or pan 8 which extends and slides through 75 said opening. As shown, the guides 7 are spaced from the two other opposite sides of the casing 1 and also spaced from the bottom 3 of the latter.

Extending transversely through the casing and disposed between and secured to the first two mentioned sides of the casing, is a pair of downwardly converging deflecting plates 9. These plates 9 are disposed beneath the inlet nipple 4, and above the tray 8 so as to direct the air entering said nipple 4 through the pipe *a* into the tray.

In using the device, the tray or pan 8 is filled with water and disposed in place in the casing. As the air passes through the 90 casing it will be directed by the plates 9 to the central portion of the tray. It will then pass along the surface of the water to the longer sides of the water pan and around these longer sides to the outlet nipple 5. 95 The particles of dust which are carried by the air as it is drawn from the pipe *a* will be collected in the tray or water pan, and may be disposed of from time to time. Should the water in the tray evaporate, it 100 may readily be replaced by withdrawing the tray either entirely or only a slight amount.

It is to be observed that the lower edges of the baffle plates 9 are spaced apart a distance considerably less than the diameter of the inlet 4, and that said edges are disposed in close proximity with the water in the pan 8. This relation of parts is highly important, as the current of air passing between said edges is flattened and then split 110 into two thinner currents which pass beneath said plates and along the surface of

the water in the pan. These two currents are practically films and it will be seen that by passing these thin films along the surface of the water, they will gather a great 5 amount of moisture therefrom, as well as depositing all dust and the like therein.

From the foregoing description, taken in connection with the accompanying drawing, the construction, use and operation of the 10 device will be readily understood. It will be seen that the objects of the invention have been effectively carried out, as an extremely simple, and yet strong and durable combined air moistener and dust collector has 15 been provided.

As various changes in form, proportion and in the minor details of construction may be resorted to without departing from the spirit of the invention, it is to be understood 20 that I do not wish to be limited to the precise construction herein shown and described.

I claim:

An air moistening and cleansing device 25 comprising a casing having an inlet opening at the center of the top and having an outlet opening at the center of its bottom, a water pan supported in said casing and extending from one to the other of two op-

posed vertical sides thereof, said water pan 30 being spaced from all other sides of said casing and having its center in alinement with the centers of said inlet and outlet openings, and a pair of deflector plates each extending from one to the other of said opposed vertical sides, said plates being downwardly inclined from the other opposed vertical sides of the casing and having their lower edges spaced apart, said edges being disposed above and adjacent to the center 40 of said water pan and the distance between said edges being less than the diameter of the inlet opening, whereby the air current is flattened prior to its contact with the water in said water pan, said flattened current 45 dividing into two thin flat currents and passing beneath said plates along the surface of the water, whereby to absorb maximum moisture from the latter and to deposit all dust and the like therein. 50

In testimony whereof I have hereunto set my hand in the presence of two subscribing witnesses.

JOHN S. NELSON.
